UNITED STATES PATENT OFFICE.

CHARLES D. MOON, OF ENSLEY, ALABAMA.

DIFFERENTIAL GEARING.

1,178,093.

Specification of Letters Patent.

Patented Apr. 4, 1916.

Application filed July 8, 1915. Serial No. 38,706.

To all whom it may concern:

Be it known that I, CHARLES D. Moon, a citizen of the United States, residing at Ensley, in the county of Jefferson and State 5 of Alabama, have invented certain new and useful Improvements in Differential Gearing, of which the following is a specification.

This invention relates to improvements in 10 machine elements, and more specifically to differential gearing.

The object of my invention is to combine 15 with a differential gearing, having the usual characteristics, oil pump means tending to act as a check when the normal action of the differential is disadvantageous. Forward motion of the vehicle frequently affords varying tractive efforts to the drive wheels, as in sandy or slippery spots in the 20 roadway. Normally the action of the differential is such that the retarded wheel, that wheel which meets the greater resistance of the good portion of the road, is given a lessening power, while the slipping wheel is 25 furnished with useless power. By employment of my novel oil pump, however, the action of the differential gearing is so checked and without shocks, that power is directed to the retarded wheel to propel the 30 car forward from the bad spot in the road, preventing stalling of the vehicle therein. The differential gears of the separated wheel axles are driven by the interlocking action 35 of the intermediate driving pinions. When the road resistance on the one wheel is increased, or lessened for the other wheel, the pinions rotate about the first wheel and tend to apply all the more power to the 40 wheel of less resistance.

Other objects of this invention not at this 45 time more particularly enumerated will be clearly understood from the detailed description and drawings forming a part of this specification.

Furthermore, this invention consists in the novel arrangement and combination of parts more particularly described in the following specification and embodied in the claims appended hereunto and forming a 50 part of this application.

Referring now to the drawings, which are merely illustrative of my invention,

Figure 1 is a vertical longitudinal sectional view of a differential housing, the oil 55 pump shown in side elevation. Fig. 2 is a transverse sectional view taken on the line

2—2 of Fig. 1. Fig. 3 is a longitudinal sectional view of the pump. Fig. 4 is a horizontal sectional view taken on the line 4—4 of Fig. 3. Fig. 5 is a detail vertical sectional view taken on the line 5—5 of Fig. 3. Fig. 6 is a detail side elevation of the connecting rod. Fig. 7 is a detail plan view of the same. Fig. 8 is a detail sectional view of oil supply tank. Fig. 9 is a detail 60 sectional view of the check-valve at the supply tank. Fig. 10 is a detail sectional view of the adjustment valve taken on the line 10—10 of Fig. 3.

Referring further to the drawings, where- 70 in similar reference characters designate similar parts throughout the respective views, 1 designates a cylindrical housing formed with a perforation 2 centrally there- through within which a drive axle 3 is 75 adapted to seat. Said housing is formed of two sections, having a plurality of bolt holes 4 spaced apart circumferentially thereof, by means of which said sections are secured together by bolts 5. Said housing is 80 bolted to a drive gear 5^a. Bevel-gears 6 are keyed to the drive axle 3 and are oppositely disposed within said housing 1. Said housing 1 is provided with oppositely disposed recesses interiorly thereof adapted to receive 85 the corner portions of a substantially rec- 90 tangular pump casing 7. Said pump casing is formed with three tubular bores longitudinally thereof, the outer bores 8 constitut- ing double cylinder pumps, each pump hav- 95 ing a pair of oppositely disposed pistons 8^a mounted therein, each pair of said pistons being connected to a similar crank arm 9 by means of pitmen 10, each arm being carried by a stub shaft 10^a and an opening 11 being 95 provided within said casing 7 to permit the rotation of said crank arm.

The centrally disposed bore 12 is pro- 100 vided with oil manifolds 13 disposed along the length thereof and adapted to connect each of the double cylinder pumps, said manifolds having adjustment valves 14 adapted to regulate the flow of oil there- through. An oil supply tank 15 is mount- ed within said bore 12 and is connected to 105 said manifolds by means of inlets 16, said inlets having check valves 17 mounted there- in. A spring operated disk 18 is mounted within said tank adapted to exert pressure 110 on the oil therein, whereby any leakage in the manifolds and pumps may be replen- ished, the check valves operating to prevent

a return of the oil to the tank. Said tank is provided with a screw cap 15^a upon one end thereof.

5 A bevel pinion 19 is mounted upon each of said stub shafts 10^a, each of said pinions being adapted to mesh with both of said bevel gears 6.

From the construction as described, it is obvious that as the main drive gear 5^a is 10 revolved by a drive shaft (not shown) of an automobile engine, the housing 1 will revolve, carrying the pump casing 7 and the pinions 19 attached thereto with it in its 15 rotation. The oil pump casing 7, being recessed within the housing 1, will revolve therewith. The bevel-pinions 19 will remain stationary with respect to said bevel gears 6, when the tractive effort upon both halves 20 of the axle is equal. However, when turning a corner or when meeting varying resistances the effect is that the retarded gear 6 is caused to rotate the pinions 19 with their respective shafts thereby operating the 25 crank arms 9 and the pistons 8, which forces the oil from one cylinder to the other through the manifolds 13. As the oil must necessarily pass through said manifolds somewhat slowly, the takeups of both halves 30 of the drive axle will be equalized, the retarded gear gaining speed slowly at the expense of the gear meeting the lessened road 35 resistance.

The utility, adaptability, and advantages of my improved form of differential gearing being obvious, it is unnecessary to further enlarge upon the same herein.

Having now described and pointed out the new and useful features of my invention, I do not limit myself to the shape of certain 40 parts where the shape is not essential, nor do I restrict myself to the exact details of construction shown and described, but mean and intend to claim all equivalents and variations thereof not departing in principle 45 from my invention, and falling within the purview of the appended claims.

What I claim as my invention and desire to secure by Letters Patent is:

1. A differential gearing consisting of a 50 housing adapted to be rotated by the driving mechanism of an automobile, bevel gears mounted upon both ends of the drive axle of said automobile, said bevel gears being oppositely disposed within said housing, bevel 55 pinions mounted upon a stub shaft interiorly of said housing and interposed between said bevel gears, a fluid pump mounted within said housing between said bevel pinions, a crank arm connecting the pistons of said pump with the stub shafts of said bevel pinion, a manifold mounted within said pump connecting the oppositely disposed cylinders thereof, a fluid reservoir mounted within said pump adapted to replenish the supply of fluid to said pump, and means mounted upon said manifolds for regulating the speed of said pump.

and a crank arm connecting the pistons of said pump with the stub shafts of said bevel pinions.

2. A differential gearing consisting of a housing adapted to be rotated by the driving mechanism of an automobile, bevel gears mounted upon both ends of the drive axle 65 of said automobile, said bevel gears being oppositely disposed within said housing, bevel pinions mounted upon a stub shaft interiorly of said housing and interposed between said bevel gears, a fluid pump mounted 70 within said housing between said bevel pinions, a crank arm connecting the pistons of said pump with the stub shafts of said bevel pinions, and a manifold mounted within said pump connecting the oppositely disposed 75 cylinders thereof.

3. A differential gearing consisting of a housing adapted to be rotated by the driving mechanism of an automobile, bevel gears mounted upon both ends of the drive axle of 80 said automobile, said bevel gears being oppositely disposed within said housing, bevel pinions mounted upon a stub shaft interiorly of said housing and interposed between said bevel gears, a fluid pump mounted within 85 said housing between said bevel pinions, a crank arm connecting the pistons of said pump with the stub shafts of said bevel pinions, a manifold mounted within said pump connecting the oppositely disposed cylinders 90 thereof, and a fluid reservoir mounted within said pump adapted to replenish the supply of fluid to said pump.

4. A differential gearing consisting of a housing adapted to be rotated by the driving 95 mechanism of an automobile, bevel gears mounted upon both ends of the drive axle of said automobile, said bevel gears being oppositely disposed within said housing, bevel pinions mounted upon a stub shaft interiorly of 100 said housing and interposed between said bevel gears, a fluid pump mounted within said housing between said bevel pinions, a crank arm connecting the pistons of said pump with the stub shafts of said bevel pinion, a manifold mounted within said pump connecting the oppositely disposed cylinders 105 thereof, a fluid reservoir mounted within said pump adapted to replenish the supply of fluid to said pump, and means mounted 110 upon said manifolds for regulating the speed of said pump.

In testimony whereof I affix my signature hereto.

CHARLES D. MOON.
